OPHTHALMIC MOUNTING

Jacob J. Pomeranz, Brooklyn, and Vincent
Tanasso, Harrison, N. Y.

Application November 22, 1939, Serial No. 305,574

1 Claim. (Cl. 88—41)

This invention relates to improvements in an ophthalmic mounting and has particular reference to a frame construction of the rimless type.

Eyeglasses have been made, heretofore, where-
in there is provided a frame including lens mem-
bers and a connecting bridge and in which said
lens members extend along the upper edges and
to the rear of the lenses in spaced relation thereto
so that said members are, at least, partially
invisible from the front of the eyeglasses. In
constructions of this kind, it has been the custom
to support each lens in position relative to the
frame merely by the use of a lens strap which is
frequently found to be inadequate to support the
rimless lens against sagging below its horizontal
axis.

It is proposed, by the present invention, to
overcome the above difficulty through the me-
dium of a lens mounting which affords a rein-
forcing structure that enables a lens to be much
more rigidly supported in front of the lens mem-
ber of a frame than has been possible heretofore.

The inventive idea involved is capable of re-
ceiving a variety of mechanical expressions one
of which, for purposes of illustration, is shown in
the accompanying drawing herein:

Figure 1 is a front elevation of an ophthalmic
mounting constructed in accordance with the
invention.

Figure 2 is an enlarged fragmentary perspec-
tive view showing the mounting for one lens, and

Figure 3 is a transverse section substantially
taken on the line 3—3 of Figure 1.

As shown in the preferred form, the mounting
comprises a frame which may be of one piece of
material and consists of a bridge 4 and curved
lens members 5 at each end of the bridge. The
outer end of the brow section of each lens mem-
ber 5 terminates in an end piece 6 to which is
pivoted the usual temple 7. The inner end or
nasal section of each lens member 5 is curved
downwardly and has associated therewith the
novel structure by means of which a lens 8 is
rigidly supported in a substantially vertical plane
in front of the associated lens member 5 with the
latter extending to the rear of and along the
upper edge of said lens in spaced relation thereto.

The structure for so mounting a lens prefer-
ably comprises a lens supporting element, gen-
erally indicated by the numeral 9. This element
may be formed from an elongated strap of bend-
able metal the main portion 10 of which is curved
to conform to the contour of the edge of the lens
which engages the same when said lens is secured

in position. For the greater part of the length of
the element 9 the same is provided upon the
inner edge of its portion 10 with an angular flange
11 which terminates short of both ends of the
portion 10 to leave the flat extremities 12 which
may be readily bent to conform to the curvature
of the lens edge. The intermediate portion of
the supporting element 9 is thus of angular form
and affords a shoe or seat in which the edge of
a lens may be seated with a considerable portion
of said edge adequately braced by engagement
with the portion 10 and the flange 11. In order
to attach or to secure the lens in position, a lens
strap 13 is provided which may be placed in
straddling position at any suitable point along
the element 9, said strap being secured to said
element by solder or any other convenient means.

The lens supporting element 9 is rigidly affixed
to the inner curved end of the lens member 5 in
spaced relation thereto by means of a two-point
connection. At one point the bight portion of
the lens strap 13 is joined to the member 5 by
the cross strap or connection 14. The second
point of connection is preferably at the inner
extremity of the lens member 5 and, in this in-
stance, the nose pad arm 15 may be employed.
This arm 15 is extended crosswise between the
member 5 and element 9 and is soldered to the
inner extremity of said member and also to the
element 9 at a point adjacent the lower extremity
12, thus leaving the latter free to be bent when
adjusting the mounting to the lens. By joining
element 9 to the lens member 5 at the two points
as just described, there is provided a rigid struc-
ture which is adequately reinforced so that, after
a lens is secured thereto, there will be very little,
if any, likelihood of a sagging of the lens from
its original adjusted position.

What is claimed is:

40 In an ophthalmic mounting, a frame member,
a bendable lens supporting element mounted in
front of said frame member and consisting of an
elongated shoe angular in cross section for a
portion of its length, a lens strap secured to said
45 supporting element adjacent one end thereof, a
cross connection between said strap and frame
member, and a nose pad arm joining said frame
member with said supporting element adjacent
the other end of the latter, the ends of said shoe
50 extending beyond said strap and arm being bend-
able so as to conform to the contour of the lens
edge engaged with said supporting element.
